UNITED STATES PATENT OFFICE.

LOUIS A. SHEPARD, OF NEW YORK, N. Y., ASSIGNEE TO CORNELIUS VANDERBILT, OF NEW YORK, N. Y.

DOOR-OPERATING MECHANISM.

SPECIFICATION forming part of Letters Patent No. 749,108, dated January 5, 1904.

Application filed March 11, 1903. Serial No. 147,207. (No model.)

To all whom it may concern:

Be it known that I, LOUIS A. SHEPARD, a citizen of the United States, and a resident of the borough of Brooklyn, city of New York, State of New York, have invented certain new and useful Improvements in Door-Operating Mechanism, of which the following is a specification.

My invention has for its object the provision of an improved door-operating mechanism for railway-cars which is characterized by lightness and ease of operation and at the same time by the great strength and power with which it holds the doors in a closed position. It furthermore provides an improved fulcrum by which the toggle arm or link may be united to the operating-beam of the doors, which fulcrum is capable of being readily removed or detached from the said beam.

The scope of the invention is defined by the appended claims.

In the drawings which accompany this specification, Figure 1 is a broken plan view illustrating my invention, together with a portion of a car-frame and the doors to which it is applied. Fig. 2 is a section on line 2 2 of Fig. 1, showing in addition certain adjacent parts of the car which are omitted from Fig. 1. Fig. 3 is a transverse vertical section taken through the axis of the toggle-joint. Fig. 4 is a detail view showing a bottom plan of the toggle-joint. Fig. 5 is a detail plan view showing the fulcrum preferably used by me, together with portions of the door-operating beam and toggle-arm. Figs. 6, 7, and 9 are enlarged top, side, and end views, respectively, of the fulcrum of Fig. 5. Fig. 8 is a sectional view of a modified form of fulcrum, and Fig. 10 is an end view of one of the members of the said modification.

The door-operating mechanism is preferably to be used in the operation of the doors used in railway-cars for the carriage of coal and other materials which are self-discharging. Such doors are often arranged in pairs and may be operated by a single beam 3, as shown in Fig. 3. Furthermore, opposing pairs of doors may be operated by a single mechanism, as the doors 1 and 2. (Shown in Figs. 1 and 2.)

My invention when the doors are arranged in pairs comprises the operating-beams 3,

which are rigidly secured at each end to the doors 1 1 and 2 2 by means of pieces 4, which are preferably castings, but may be of any other suitable material, such as pressed metal, &c. The beams 3 are preferably flanged beams of ordinary commercial form—such as I-beams, T-beams, &c.—and may be either of rolled or pressed metal. At the middle of the said beam 3 the fulcrum is secured. The said fulcrum may be either a single piece 5, as shown in Figs. 1 and 2, or it may be composed of two or more parts secured together and to the beam 3, as the fulcrums of Figs. 5 to 9 or as the fulcrum shown and claimed in my application, Serial No. 125,746, filed October 3, 1902. To these fulcrums are pivoted the ends of the toggle-arms 6 6. These arms are connected together by a knuckle-joint whose axis is permitted to fall just below the center line connecting the axes of the fulcrum-joints, and thereby hold the doors 1 and 2 with great firmness in a closed position. I further provide means for raising the central axis of the toggle-arms, and thereby drawing the beams 3 toward each other and opening the doors. The said means may be of any approved construction, such as a link 7, connected at its lower end to the pin 8, forming the axis of the toggle-joint, and at its upper end connected to an arm 9, fixed upon the horizontal shaft 10. The said shaft is preferably journaled in bearings 11 and 12, supported by the center sill 13 and side wall 14 of the car, as shown in Fig. 1. One end of the said shaft carries a notched plate 15, adapted to be engaged by the locking-dog 16, and thereby firmly held.

In order to keep the axis 8 of the toggle-joint in a vertical path when raised by the arm 9 and link 7, I provide each of the toggle-arms with a laterally-extending lug or projection 18, which is situated at some distance from the said axis or pin 8. Vertical guides are provided for the said lugs and may consist of angle-beams 19, as shown. In place of the said beams, however, I may substitute therefor channels, or instead of using a single angle, as shown, a pair of angles may be used, between which the lugs may operate. It is obvious that any other form of vertical guide may be used, however.

It is evident that in case single doors 1 and

2 are arranged opposite each other the beams 3 may be dispensed with and the toggle-arms 6 applied directly to the doors.

The fulcrum illustrated in Figs. 5, 6, 7, 5 and 9 is composed of two similar complementary pieces or members 21 22, each of which carries a jaw 23, which together form the fork to which the toggle-arm is to be secured. The ends of the pieces 21 22 opposite the jaws 23 terminate in the flattened end portions 24, which are perforated and adapted to be clamped by a rivet or other suitable means against opposite faces of the web of the flanged beam 3. The intermediate or body portions of the members 21 and 22 are so shaped as to provide deep grooves or recesses 26, which receive the flanges of the I-beam 3. These portions are also provided with sloping shoulders or angular projections 27 27, which abut and interlock when the members 21 and 22 are brought together.

Each of the jaws 23 is provided with a perforated boss 28. These bosses occupy similar relative positions with respect to the jaws, and when the members 21 and 22 are brought together the bosses 28 abut against each other and may be secured in this position by a rivet or bolt 29 passing through their centers, as best seen in Fig. 6. The jaws 23 are also bored with pin-holes 30 for the purpose of securing the toggle-arm thereto. By this construction when the members 21 and 22 are fitted together around the flanges of the beam 3 and the rivets inserted a very firm and rigid union of parts is secured.

In place of the bosses 28 and rivets 29 I may use a shouldered rivet 31, Figs. 8 and 10, rigid with one of the jaws 23 and provided 40 with a shoulder 32 and a shank 33. When the members 21 and 22 are brought together, the shoulder 32 bears against the opposite jaw 23, while the shank 33 passes through an aperture in the latter jaw and may be riveted, 45 as shown in Fig. 8.

It will be obvious that the improved fulcrums which I have described as connecting the beam 3 and toggle-arm 6 may be used for uniting any operating-lever to a flanged beam—as, for example, for uniting a brake-lever to a brake-beam.

What I claim, and desire to secure by Letters Patent, is—

1. In a car, a pair of hinged discharge-doors,

It is hereby certified that in Letters Patent No. 749,108, granted January 5, 1904, upon the application of Louis A. Shepard, of New York, N. Y., for an improvement in "Door-Operating Mechanisms," an error appears in the printed specification requiring correction, as follows: In line 37, page 2, the word "rivets" should read "rivet," and that the said Letters Patent should be read with this correction therein that the same may conform to the record of the case in the Patent Office.

Signed and sealed this 19th day of January, A. D., 1904.

[SEAL.]

a flanged beam rigidly united thereto at each 55 end, a fulcrum comprising a plurality of separable parts, removably secured to the middle portion of said beam, and a door-operating arm or link connected to said fulcrum, substantially as described.

2. In a car, hinged doors, toggle-arms connected thereto, said toggle-arms being connected together by a knuckle-joint, lugs or projections on said toggle-arms removed from their axis, and vertical guides for said lugs, 60 substantially as described.

3. In a car, hinged doors, toggle-arms connected thereto, lugs or projections on said toggle-arms removed from their axis, vertical guides for said lugs and means for raising the axis of said toggle-arms, substantially as described.

4. In a car, hinged doors, toggle-arms connected thereto, lugs or projections on said toggle-arms removed from their axis, vertical 75 guides for said lugs, a link connected to the axis of said toggle-arms, a rock-shaft having an arm connected to said link, and means for holding said rock-shaft, substantially as described.

5. A fulcrum for flanged beams, comprising two members recessed to receive between them the flange of the beam, and having flattened securing portions on one side of said recesses, and angular projections which abut and interlock on the opposite side of said recesses, in combination with means for clamping said members together on both sides of said recesses, substantially as described.

6. A fulcrum for flanged beams, comprising 80 two members having flat end portions for engagement with the opposite faces of the web of the beam, immediate recessed portions to receive the flanges of the beam, and end portions or jaws to form a fork, one of which end 95 portions is provided with an aperture and the other of which is provided with a rivet or post adapted to pass through said aperture said rivet having a shoulder to abut against the part surrounding said aperture, substantially as described.

In witness whereof I have hereunto set my hand this 10th day of March, 1903.

LOUIS A. SHEPARD.

In presence of:

EDWIN C. FARLOW,
BERTRAM G. SMITH.

2 are arranged opposite each other the beams 3 may be dispensed with and the toggle-arms 6 applied directly to the doors.

The fulcrum illustrated in Figs. 5, 6, 7, 5 and 9 is composed of two similar complementary pieces or members 21 22, each of which carries a jaw 23, which together form the fork to which the toggle-arm is to be secured. The ends of the pieces 21 22 opposite the jaws 23 terminate in the flattened end portions 24, which are perforated and adapted to be clamped by a rivet or other suitable means against opposite faces of the web of the flanged beam 3. The intermediate or body portions of the members 21 and 22 are so shaped as to provide deep grooves or recesses 26, which receive the flanges of the I-beam 3. These portions are also provided with sloping shoulders or angular projections 27 27, which abut and interlock when the members 21 and 22 are brought together.

Each of the jaws 23 is provided with a perforated boss 28. These bosses occupy similar relative positions with respect to the jaws, and when the members 21 and 22 are brought together the bosses 28 abut against each other and may be secured in this position by a rivet or bolt 29 passing through their centers, 25 as best seen in Fig. 6. The jaws 23 are also bored with pin-holes 30 for the purpose of securing the toggle-arm thereto. By this construction when the members 21 and 22 are fitted together around the flanges of the beam 3 30 and the rivets inserted a very firm and rigid union of parts is secured.

In place of the bosses 28 and rivets 29 I may use a shouldered rivet 31, Figs. 8 and 10, rigid with one of the jaws 23 and provided 40 with a shoulder 32 and a shank 33. When the members 21 and 22 are brought together, the shoulder 32 bears against the opposite jaw 23, while the shank 33 passes through an aperture in the latter jaw and may be riveted, 45 as shown in Fig. 8.

It will be obvious that the improved fulcrums which I have described as connecting the beam 3 and toggle-arm 6 may be used for uniting any operating-lever to a flanged beam—as, for example, for uniting a brake-lever to a brake-beam.

What I claim, and desire to secure by Letters Patent, is—

1. In a car, a pair of hinged discharge-doors,

It is hereby certified that in Letters Patent No. 749,108, granted January 5, 1904, upon the application of Louis A. Shepard, of New York, N. Y., for an improvement in "Door-Operating Mechanisms," an error appears in the printed specification requiring correction, as follows: In line 37, page 2, the word "rivets" should read "rivet," and that the said Letters Patent should be read with this correction therein that the same may conform to the record of the case in the Patent Office.

Signed and sealed this 19th day of January, A. D., 1904.

[SEAL.]

a flanged beam rigidly united thereto at each 55 end, a fulcrum comprising a plurality of separable parts, removably secured to the middle portion of said beam, and a door-operating arm or link connected to said fulcrum, substantially as described.

2. In a car, hinged doors, toggle-arms connected thereto, said toggle-arms being connected together by a knuckle-joint, lugs or projections on said toggle-arms removed from their axis, and vertical guides for said lugs, 60 substantially as described.

3. In a car, hinged doors, toggle-arms connected thereto, lugs or projections on said toggle-arms removed from their axis, vertical guides for said lugs and means for raising the axis of said toggle-arms, substantially as described.

4. In a car, hinged doors, toggle-arms connected thereto, lugs or projections on said toggle-arms removed from their axis, vertical 75 guides for said lugs, a link connected to the axis of said toggle-arms, a rock-shaft having an arm connected to said link, and means for holding said rock-shaft, substantially as described.

5. A fulcrum for flanged beams, comprising two members recessed to receive between them the flange of the beam, and having flattened securing portions on one side of said recesses, and angular projections which abut 85 and interlock on the opposite side of said recesses, in combination with means for clamping said members together on both sides of said recesses, substantially as described.

6. A fulcrum for flanged beams, comprising 90 two members having flat end portions for engagement with the opposite faces of the web of the beam, immediate recessed portions to receive the flanges of the beam, and end portions or jaws to form a fork, one of which end 95 portions is provided with an aperture and the other of which is provided with a rivet or post adapted to pass through said aperture said rivet having a shoulder to abut against the part surrounding said aperture, substantially as described.

In witness whereof I have hereunto set my hand this 10th day of March, 1903.

LOUIS A. SHEPARD.

In presence of

EDWIN C. FARLOW,
BERTRAM G. SMITH.

Correction in Letters Patent No. 7

It is hereby certified that in Letters Patent No. 749,108, granted January 5, 1904, upon the application of Louis A. Shepard, of New York, N. Y., for an improvement in "Door-Operating Mechanisms," an error appears in the printed specification requiring correction, as follows: In line 37, page 2, the word "rivets" should read *rivel*; and that the said Letters Patent should be read with this correction therein that the same may conform to the record of the case in the Patent Office.

Signed and sealed this 19th day of January, A. D., 1904.

[SEAL.]

F. I. ALLEN,
Commissioner of Patents.
